UNITED STATES PATENT OFFICE.

OTTO WETTSTEIN, OF ROCHELLE, ILLINOIS.

DESIGN FOR A BADGE.

SPECIFICATION forming part of Design No. 15,880, dated February 24, 1885.

Application filed December 4, 1884. Term of patent 7 years.

To all whom it may concern:

Be it known that I, OTTO WETTSTEIN, residing at Rochelle, in the county of Ogle and State of Illinois, and a citizen of the United States, have invented a new and original Design for Badge-Pins, of which the following is a full description, reference being had to the accompanying drawing, in which the figure is a face view illustrating my design.

10 My design consists in an oval-shaped badge, having the view face thereof divided into inner and outer panels lying within parallel lines, corresponding to the curvature of the periphery of the badge, with a central division 15 by the representation of a torch, and contrasting shades on the opposite sides of such torch, one side of the torch displaying a rising sun and the other displaying the moon and stars, as clearly shown in the drawing.

20 A represents the badge, which, as shown, is oval, with its periphery of an oval shape, and having on its view face an outer and inner circle corresponding in curvature to that of the periphery. The view face of this badge is divided at the center by the representation of a torch, and on each side of this torch this face of the pin is arranged in contrasting shades, and the darker shade has therein in lighter colors on the innermost panel the configuration of stars and crescent.

30 The innermost panel of the lighter shade has thereon the sun. The surface thus viewed presents to the eye the inner and outer panels of contrasting shades divided by the representation of a torch, the one having thereon 35 the stars and crescent and the other the rising sun, as clearly defined in the drawing.

I claim—

The design for a badge herein shown and described, the whole consisting of an oval 40 shape, with its view face having inner and outer panels and a dividing torch, with the panels in contrasting shades each side of the torch, and having thereon the stars and crescent and rising sun, as shown and described.

OTTO WETTSTEIN.
